(57) **CLAIM**

The ornamental design for a tray for printer cartridges, as shown and described.

DESCRIPTION

FIG. 1 is a right side elevational view of a tray for printer cartridges showing our new design;

FIG. 2 is a top plan view thereof;

FIG. 3 is a front elevation view thereof;

FIG. 4 is a rear elevational view thereof;

FIG. 5 is a left side elevational view thereof;

FIG. 6 is a bottom plan view thereof;

FIG. 7 is a top, rear, right side perspective view thereof;

FIG. 8 is a bottom, front, left side perspective view thereof;

FIG. 9 is a top, rear, left side perspective view thereof; and,

FIG. 10 is a bottom, front, right side perspective view thereof.

The broken lines depict environmental subject matter only and form no part of the claimed design.
